UNITED STATES PATENT OFFICE

122,844

DESIGN FOR AN ELECTRIC CONTROL PANEL BOARD UNIT

Elwood T. Platz, Detroit, Mich.

Application February 10, 1940, Serial No. 90,176

Term of patent 14 years

To all whom it may concern:

Be it known that I, Elwood T. Platz, a citizen of the United States and a resident of Detroit, Michigan, have invented a new, original, and ornamental Design for an Electric Control Panel Board Unit, of which the following is a specification, reference being had therein to the accompanying drawings.

In these drawings,

Fig. 1 is a perspective front view of an electric control panel board unit showing my new design;

Fig. 2 shows a unit thereof, in front view;
Fig. 3 is a sectional view.

I claim:

The ornamental design for an electric control panel board unit, substantially as shown.

ELWOOD T. PLATZ.
